CLAIM

The ornamental design for an electrical connector assembly, as shown and described.

DESCRIPTION

FIG. 1 is a top perspective view of the first connector of an electrical connector assembly showing our new design; FIG. 2 is a front view of the first connector; FIG. 3 is a rear view of the first connector; FIG. 4 is a left side view of the first connector; FIG. 5 is a right side view of the first connector; FIG. 6 is a top plan view of the first connector; FIG. 7 is a bottom plan view of the first connector; FIG. 8 is a top perspective view of the second connector of an electrical connector assembly showing our new design; FIG. 9 is a front view of the second connector; FIG. 10 is a rear view of the second connector; FIG. 11 is a left side view of the second connector; FIG. 12 is a right side view of the second connector; FIG. 13 is a top plan view of the second connector; FIG. 14 is a bottom plan view of the second connector; and, FIG. 15 is a top perspective view of the first connector and the second connector of an electrical connector assembly showing our new design.

The broken line showing of the environment is for illustrative purposes only and forms no part of the claimed design.
